DESIGN FOR A COMBINATION ENVELOPE OPENER AND PAPER CUTTER

Andrew M. Lockett, New Orleans, La.

Application September 20, 1941, Serial No. 103,433

Term of patent 7 years

To all whom it may concern:

Be it known that I, Andrew M. Lockett, a citizen of the United States, residing in New Orleans, State of Louisiana, have invented a new, original, and ornamental Design for a Combination Envelope Opener and Paper Cutter, of which the following is a specification, reference being had to the accompanying drawing, forming part thereof.

In the drawing,

Fig. 1 is a front elevational view of a combination envelope opener and paper cutter showing my new design;

Fig. 2 is a side view thereof;

Fig. 3 is a rear elevational view thereof; and

Fig. 4 is a view of the side opposite that shown in Fig. 2.

I claim:

The ornamental design for a combination envelope opener and paper cutter, substantially as shown.

ANDREW M. LOCKETT.
